(57) **CLAIM**

The ornamental design for a cover for vehicle seat as shown and described.

DESCRIPTION

2. Cover for vehicle seat

2.1 : Front

2.2 : Back

2.3 : The view in use state

2.4 : The view in use state

The pale tonal overlay bounded by broken lines in reproductions 2.3 and 2.4 identifies environmental vehicle seat portions included for the purpose of demonstrating a state of use, and form no part of the claimed design.
